[57] CLAIM

The ornamental design of a restaurant building, substantially as shown and described.

DESCRIPTION

FIG. 1 is a perspective view of the restaurant building taken from a location above and off to one side from the front of said building;

FIG. 2 is a front elevational view thereof;

FIG. 3 is a rear elevational view thereof;

FIG. 4 is a side elevational view of the left side of the restaurant building; and

FIG. 5 is a side elevational view of the right side of the restaurant building.

FIG. I

FIG. 2

FIG. 3

FIG. 4

FIG. 5
